APPARATUS FOR AUTOMATICALLY FEEDING METAL PIGS

Vincent Tobia, Chandlers Ford, England, assignor to Pirelli-General Cable Works Limited, London, England, a British Company

Application December 4, 1935, Serial No. 52,795
In Great Britain December 8, 1934

16 Claims. (Cl. 198—35)

The present invention relates to apparatus for automatically feeding metal pigs to a melting pot and is particularly, although not necessarily exclusively, applicable for feeding lead or lead alloy pigs to the melting pot of an extrusion machine. It is customary to store the pigs in groups comprising layers, each containing the same number of pigs, but those in each layer being disposed at right angles to those in the layers immediately above and below. In the case of lead or lead alloy pigs, it is common to store them in groups of twenty-five, comprising five layers of five pigs each. It is, however, desirable to feed the pigs into the melting pot one at a time at regular intervals, the chief advantages accruing being that the variation in temperature of the molten metal in the pot due to the introduction of the solid pigs is minimized, and this is also the case in respect of the level of the molten metal, with the result that the sides of the melting pot are not subjected to the action of the dross, which forms on the surface of the molten metal and which becomes attached to the walls of the pot at that surface, to the same degree as is the case if there be considerable variation in level. A further advantage lies in the fact that, when using alloys, the maintenance of the correct proportion of the constituents in the melting pot is facilitated if the pigs are fed in at a uniform rate with the resultant minimization of temperature variation. The present invention has for its main object to facilitate the handling of the pigs in groups as above described and their feeding into the melting pot one by one at regular intervals.

The invention consists in apparatus comprising a travelling belt or like conveyor on which the groups of pigs may be placed and a co-operating elevator having one or more cradles adapted to lift the pigs one layer at a time and to deliver them on to a delivery device, such as a chute or roller platform, provided with means for detaining the pigs constituting the layer and releasing them one by one at regular intervals into the melting pot. For the purpose of supporting the groups of pigs, the travelling belt, arranged so that its upper operative length is substantially horizontal, is fitted with a series of revolute tables, each of a size and shape suitable to receive one group of pigs. The elevator with which the travelling belt co-operates may be constituted by two chains passed over upper and lower pairs of sprocket wheels, the rising and falling portions of the chains being substantially vertical and the wheels in each pair being connected so

as to rotate together. In this case there is provided a number of cradles each serving to lift a layer of pigs and constituted by two members, one on each of the chains, and pivoted thereto so as to be capable of swinging toward or away from each other for the purpose of engaging or releasing a layer of pigs. In an alternative construction, there is a single cradle only arranged to travel upwardly with a single layer of pigs, to deposit them on to the delivery device and then to return by the same path for a second layer.

In either of the above constructions, since, as above mentioned, the pigs in each layer extend in a direction at right angles to those in the layers above and below, it is necessary that, after each layer has been lifted by the elevator, the group of pigs shall be rotated through a right angle about the vertical axis in order that, when the time comes for lifting the next layer, the pigs therein shall extend in the correct direction for engagement by the cradle. Accordingly, mechanism, automatically operated in sequence with the conveyor and elevator, is provided for periodically rotating the table which, for the time being, is in position for co-operation with the elevator.

In order that the invention may be clearly understood and readily carried into effect, it will now be described more fully with reference to the accompanying drawings which illustrate two forms of apparatus in accordance therewith and wherein:—

Figure 1 is a side elevation of one form of apparatus comprising conveyor and elevator units, certain gear-wheels being shown in chain-dotted lines only in order to avoid obscuring parts lying behind them.

Figure 2 is a side view of the elevator unit to an enlarged scale,

Figure 3 is a section on the line A—A of Figure 1 to the scale employed in Figure 2,

Figure 4 is a partial section on the line A—A of Figure 1 to a still further enlarged scale,

Figure 5 is a plan view of a detail on the line B—B of Figure 4,

Figure 6 is a side elevation of a modified form of apparatus,

Figures 7 and 8 are respectively side view and plan of certain details of the modified apparatus illustrated in Figure 6, but to a larger scale, certain other features being omitted or shown chain-dotted for the sake of clearness,

Figure 9 is an end elevation of a portion of the elevator unit shown in Figure 6 seen from the right-hand side,

Figure 10 is a similar view as seen from the left-hand side.

Figures 11 and 12, together constituting a single diagram, illustrate the electrical circuits 5 of the apparatus described with reference to Figures 6 to 10.

Referring to Figures 1 to 5, the metal pigs 1, normally stacked in groups of five layers, each layer comprising five pigs as shown, are supported on a series of tables 2, each rotatable about an axis at right angles to its surface. In Figure 1 six of such tables are shown, but it is to be understood that any number may be employed and, in fact, in Figure 4 a further table is 10 shown in the inverted position which each table occupies in succession in the manner described below. Each of the rotatable tables 2 is supported by means of a ball race 3 from a non-rotatable frame 4, connected by means of lugs 5 with two endless conveyor chains 6 passed around 15 pairs of sprocket wheels 7 and 8 located respectively at opposite ends of the apparatus, so that the portions of the conveyor chain 6 lying between them extend in substantially horizontal directions. The weight of the tables 2 and their 20 supporting frame 4 as well as of the groups of pigs 1 which may be placed on the tables is taken by channel guides 9 and 10 extending respectively over the length of the conveyor unit, and with 25 which rollers 11, carried by the frames 4 and extending laterally therefrom, are adapted to co-operate. The groups of metal pigs 1 are loaded on to their respective tables 2 when each of the latter is near the right-hand end of the conveyor 30 unit, as seen in Figure 1; the tables are then caused to travel to the left toward the elevator unit under which each group of pigs remains stationary for a sufficient period to allow the pigs to be dealt with by the elevator unit in the manner described below.

In order to secure the necessary periodic motion of the conveyor unit, the sprocket wheels 8 are driven from a continuously running shaft 12 which, as described below, also serves to drive the elevator; on the shaft 12 there is a pinion 13 meshing with a gear wheel 14 mounted on a spindle 15. Fast on the spindle 15 there is also a toothed segment 16 which gears with a toothed wheel 17 on the spindle 18 of the sprocket wheels 8. Thus, although the spindle 12 revolves continuously, the sprocket wheels 8 are rotated intermittently, and the above-described gearing is so designed that the period during which the conveyor chain 6 is stationary occurs while one 45 of the groups of metal pigs 1 is in its operative position relatively to the elevator and is by this means caused to remain there for a sufficiently long period to allow of all the pigs being dealt with by the elevator. The sprocket wheels 8 are 50 then rotated by the above-described gearing to a sufficient degree to bring the group of pigs next in succession into the operative position relatively to the elevator where it remains for a like period and the sequence of operations is repeated.

The elevator unit comprises a pair of endless chains 19 each encircling upper and lower sprocket wheels 20, 21. The lower sprocket wheels 21 are mounted on the driving shaft 12 so that the sprocket wheels and elevator chains are continually in motion in such a direction that the right-hand portions of the chains, as seen in Figures 1 and 2, move in the upward direction. Attached to the elevator chains 19 is a series of five cradles, each comprising two swinging members 22 respectively pivoted at 23 to the chains 19, the

pivots being, as clearly seen in Figure 3, so located as to enable the members 22 to swing toward or away from each other. The members 22 are provided with inwardly directed extensions 24 adapted to engage underneath lugs 25 formed at opposite ends of each of the metal pigs 1, whereby, as clearly appears from Figure 3, each cradle on its upward travel is adapted to lift a layer of metal pigs. By mechanism described below each pair of swinging members 22 is caused to lift the layer of pigs 1 which, for the time being, is uppermost in its group, to carry it over the highest position to which the chain 19 travels around the sprocket wheel 20 and then to begin lowering the layer of metal pigs until the latter come into contact with a delivery device consisting of an inclined platform comprising a series of rollers 26 on which the pigs are deposited. In order that, when the chains 19 pass over the upper portion of the sprocket 20 the cradles shall remain in their depending position, each of the pivots 23 is itself pivoted at 27 in such a direction as to permit the corresponding member 22 to swing in a plane parallel to that of either chain 19. Thus the extensions 24 engaging the lugs 25 remain substantially horizontal and serve to support the metal pigs 1 until the latter make contact with and are borne by the rollers 26. After thus discharging the metal pigs, the cradles continue their downward motion until, having passed around the lower sprocket wheel 21, each is again brought to the position in which it serves to lift the layer of pigs which, for the time being, is uppermost in the group which meanwhile has been brought by the conveyor to the operative position.

In order to effect this selection of the uppermost layer of pigs, each swinging member 22 is fitted with an upwardly directed arm 28 having a transverse bar 29 adapted, as the elevator chains travel upwards, to engage at its opposite ends one pair of a series of cam plates 30. As seen in Figure 3, in proximity to its lower extremity, each of these cam plates is so shaped that, as the transverse bar 29 comes into contact with the pair with which it co-operates, it is urged inwardly so as to cause the corresponding member 22 to rock in such a manner as to bring its inwardly directed extension 24 clear of the metal pigs. As, however, the cradle continues to ascend, the bars 29 clear the upper edges of the corresponding cam plates 30 so that the members 22 swing inwardly and this action is arranged to occur at such a moment that the extensions 24 are caused to engage beneath the lugs 25 of the layer of pigs which, for the time being, is uppermost; obviously, this must take place at progressively lower positions as occupied by the successive cradles in the series. Thus, in the apparatus illustrated, there are five cradles corresponding to the number of layers of pigs 1 in each group, and the cradle which, as shown in Figure 2, is approximately at the middle of its ascent, has functioned to lift the topmost layer in the group. For this purpose, the members 22 must be separated for a sufficient length of their travel to clear the metal pigs in the four lower layers and the co-operating cam plates 30 are, accordingly, of sufficient length to prevent the release of these members until the extensions 24 are opposite the topmost layer of pigs. The action of the succeeding cradle, however, must be such as to clear only the three lower layers of pigs and engage the fourth which is now the uppermost layer. Accordingly, the cam plates 30 adapted to co-oper-

ate with the bars 29 of this cradle must be correspondingly shorter: similarly, those which co-operate with succeeding cradles must be made correspondingly shorter still. This construction 5 is clearly illustrated in Figure 2, from which it will also be seen that the bars 29 vary correspondingly in length, the bars on the members 22 constituting the first cradle being made sufficiently long to co-operate with the longest pairs of cam 10 plates which are located respectively at the outside of each series. The next shorter pairs of cam plates 30 are located immediately within the longest pairs and correspondingly the bars 29 on the members 22 of the next succeeding cradle 15 are shortened so as to engage with these pairs of cam plates 30. Similarly the cam plates 30 constituting the succeeding pairs progressively decrease in length and in distance apart and the bars 29 adapted respectively to co-operate with 20 them are correspondingly of progressively decreased length as shown in Figure 2.

For the purpose of rotating the group of pigs in operative position under the elevator, through a right angle after each layer of pigs has been 25 lifted, there is provided a turntable occupying such a position that it is immediately underneath the rotatable table 2 bearing the group of pigs being operated on by the elevator. This turntable and each of the tables 2 are provided 30 with mutually acting engagement mechanism: the turntable comprises a disc 31, Figures 4 and 5, on which there are two dogs 32 separated by a parallel-sided space 33. As the tables 2 are drawn forward by the conveyor chains 6, the disc 31 is in the position shown in Figures 4 and 5, that is to say, the parallel-sided space 33 lies in the direction of travel so that a squared projection 34 from the underneath of the rotatable table 2 which is about to be brought beneath the 35 elevator may enter the space 33, and correspondingly the way is clear for the table which has been emptied by the elevator to proceed on its course. As indicated, particularly in Figure 5, each of the squared projections 34 is of such a 40 width as to engage the parallel inner faces of the dogs 32, so that, on the disc 31 being rotated, the table 2 is rotated with it. For the purpose of rotating the disc 31 and dogs 32, there is provided a continuously revolving shaft 35 driven 45 in any suitable manner such, for example, as by means of bevel gearing from the shaft 12. On the shaft 35 there is a worm 36 meshing with a worm wheel 37 fitted with an upwardly projecting stud 38 adapted to engage a projection 39 50 on a band 40 comprising one element of a friction drive. The other element comprises a drum 41 and between the band 40 and drum 41 there is interposed a suitable friction lining 42. The disc 31 and drum 41 are fixed on a spindle 43, 55 on which the worm wheel 37 is loosely mounted; thus the disc 31 is continuously rotated from the shaft 35 through the worm gearing and friction drive, unless it is forcibly prevented from doing so, in which case the friction drive allows for slipping.

Obviously, as soon as a layer of pigs has been lifted by one of the cradles, the group of pigs should be rotated through a right angle and then held stationary until the next layer has been 60 lifted by the succeeding cradle. For the purpose of thus allowing rotation and then arresting the group of pigs, the disc 31 is provided with a series of projections 44 adapted to be engaged in turn by a plunger 45 mounted so that it can oscillate 65 in a stationary guide 46 and jointed to a lever

47 pivoted at 48. The opposite end of the lever 47 is provided with a cam roller 49 adapted to co-operate with a cam 50 on the shaft 12. The design and timing of the cam 50 are such that immediately a layer of pigs has been lifted from the group under the elevator, the plunger 45 is withdrawn from engagement with one of the projections 44, thus permitting rotation of the disc 31 and with it the table 2 and its layer of pigs which is in the operative position. Before, however, rotation through a right angle has been completed, the cam 50 has operated to allow restoration, by such means as a spring not shown, of the plunger 45 to or toward its original position so that it is encountered by the next succeeding projection 44, whereupon the rotation of the disc 31 and consequently of the group of pigs in the operative position is arrested, the layer of pigs which is now uppermost being then in correct position for engagement with the cradle operating next in sequence: Figures 1 and 2 are drawn to depict this action as having already taken place.

After the lowest layer of pigs in a group has been lifted, obviously time must be allowed for bringing the next succeeding group beneath the elevator: for this reason, as seen in Figures 1 and 2, the cradles are not equispaced along the elevator chains, the space between the cradle adapted to lift the lowest layer and that operating on the topmost layer being longer than those between the remaining cradles.

Since the roller platform 26, on to which the pigs are delivered layer by layer, is inclined, the pigs in each layer roll down it so as to make way for delivery of those constituting the next layer. For reasons above mentioned, however, it is desirable that the pigs should be delivered to the melting pot one at a time, and for this purpose, there is provided a detaining and releasing device, comprising a detent 51 pivoted at 52 and adapted to be rocked by means of a connecting rod 53 from a crank disc 54. This disc is fitted on a spindle 55 driven by chain gearing 56 from the spindle 57 on which the sprocket wheels 20 are mounted. The detent 51 is formed with two arms 58 and 59 and the arrangement is such that, on the detent being rocked, these arms project alternately above the level of the rollers 26. For instance, in Figure 2, it will be seen that the arm 58 is so projecting and is consequently preventing the pigs from sliding off the roller platform 26. On further rotation of the crank disc 54, however, the arm 58 will be depressed below the level of this platform, but previously to this action the arm 59 has risen so that the foremost pig only is free to slide off the platform, the remainder being detained by the arm 59. Continued rotation of the crank disc 54 results in depression of the arm 59 and elevation of the arm 58, when the remaining pigs slide down the roller platform 26, but are arrested by the arm 58, which has been elevated. The sequence of operations is then repeated so that the pigs are released one by one. On leaving the roller platform 26, each pig runs on to a second roller platform 60 extending at right angles to the roller platform 26, whence it is delivered to the melting pot.

The apparatus illustrated in Figures 6 to 10 is 70 of the same general type as that above described, comprising, namely a conveyor unit adapted to co-operate with an elevator unit by which the pigs are delivered to a delivery device adapted to feed them to the melting pot one at a time. As 75

in the previous case, the metal pigs 1 are mounted on a series of tables 2 connected with an endless conveyor chain 6 passing around sprocket wheels 7 and 8. The elevator, however, although 5 of the type comprising an endless chain passing around upper and lower sprocket wheels 20 and 21, does not operate continuously in the same direction, nor is it provided with a series of cradles. Instead thereof there is a single cradle unit which 10 is caused to travel upwardly and, having reached its highest point as determined by the upper sprocket wheel 20, to move downwardly so as to deposit its load of pigs on to the roller platform or like delivery device 26 and then to return by 15 the same path for a further layer of pigs. The conveyor and elevator are respectively driven by separate electric motors 61, 62, each operating through suitable gearing, while a third electric motor 63 serves to actuate the turntable mechanism. Obviously, none of these motors is required to run continuously in the same direction and they are automatically controlled both manually by "start" and "stop" press buttons and automatically by the various movements of the apparatus in the manner described below. Indications are given on the drawings of the various switches actuated by the apparatus during the course of its operation, but it is to be understood that, generally speaking, such representations are 20 of a diagrammatic nature and are not intended to afford any indication of the actual construction of switches employed.

In the apparatus now under consideration, six tables are employed, as indicated in Figure 6, the 35 loading position for each of these being, as in the previously described apparatus, toward the right-hand end of the machine as seen in Figure 6. In order to load each table, it is necessary that the conveyor should be stopped with the 40 table in its appropriate position, and for this purpose there is provided a switch A adapted, as the conveyor chain 6 travels in such a direction as to bring the tables toward the elevator, to be actuated by means of one of a series of buttons, 45 rollers or the like 64. These are carried by the chain 6 in such positions relatively to the various tables as to actuate the switch A successively when the various tables arrive at the loading position. Due to such actuation, the circuit of the 50 motor 61, which has hitherto been running in order to drive the conveyor, is broken and the conveyor therefore stops. The construction of the switch A is, however, such that after a few seconds it again closes, but during that period the 55 circuit of the motor 61 has been opened by the control apparatus at another point, so that the motor does not restart on the automatic closing of the switch A. When, however, the loading operation on to the particular table in the loading position has been completed, the "start" press button of the apparatus is operated manually, resulting in the restarting of the motor 61 and the 60 travel forward of the conveyor until the next following table has arrived at the loading position, whereupon the conveyor is again stopped automatically and the sequence of operations repeated.

For the purpose of arresting the tables successively in the position in which the elevator 70 may operate on the groups of pigs thereon, a switch B is provided. This is adapted to be successively actuated by a second series of buttons, rollers or the like 65, suitably located along the chain 6. The switch B also operates to interrupt 75 the circuit of the motor 61 and then auto-

matically to reclose itself, but not until the motor circuit has been interrupted by another switch, the action of which is described below.

As above mentioned, the elevator is provided with a single cradle only. This comprises a pair 5 of swinging members 66, seen most clearly in Figures 9 and 10, having inwardly directed projections 67 adapted to lift the uppermost layer in the previously described apparatus. The members 66 are pivoted at 68 to a cross beam 69 adapted to slide in vertical guides 70. In Figure 9 the cradle is depicted in full lines as travelling in the downward direction and in chain-dotted lines as having engaged the uppermost layer of 15 pigs and about to commence its upward travel. Obviously, the lowest point to be reached by the cradle must be determined by the height of the particular layer of pigs which, for the time being, is uppermost; that is to say, if a group of pigs 20 has just been introduced beneath the elevator, the downward travel of the cradle must be a minimum in order that it shall engage and lift only the topmost layer of pigs. On its next journey, however, it must reach a lower point in order to engage the second layer and, on subsequent journeys, it must travel to successively lower 25 positions.

In order to determine the point of reversal, the cross beam 69 is provided with a plunger 71, 30 which, on the downward travel of the cradle, comes into contact with the upper surfaces of the pigs in the uppermost layer for the time being. Motion of this plunger is, therefore, arrested, but, as the cross beam 69 continues to travel downwardly, the plunger slides through it. The plunger is provided with upper and lower collars 72 and 73: these collars co-operate with one arm of a bell-crank lever 74 pivoted at 75 to a bracket carried by the cross beam 69. The other arm of 40 the bell-crank lever 74 is jointed to a plunger 76 mounted in a guide 77 on the cross beam 69 so as to be capable of motion in the horizontal direction, and it will be seen that, on arrest of the plunger 71 by contact with the uppermost 45 layer of pigs, such horizontal motion of the plunger toward the left, as seen in Figure 9, will occur. When this takes place, the plunger is opposite some portion of a swinging frame 78 which extends vertically over a height approximately equal 50 to that of a complete group of pigs; the frame 78 is supported by pivoted links 79 and is spring biased in a direction opposite to the above motion of the plunger 76. The frame 78 co-operates with a switch C which, on actuation, is effective 55 to reverse the motor 62 which drives the elevator. This action occurs at the moment when the extensions have engaged the layer of pigs uppermost for the time being and results in the downward motion of the cradle being stopped and its 60 upward motion with the layer of pigs commencing.

The cradle rises to its highest position as determined by the travel of the elevator chain over the sprocket wheel 20, moves across to the opposite 65 side of the elevator in a manner similar to that followed by the cradles in the previously described apparatus, and then descends so that the pigs are deposited on to the roller platform or like delivering device 26, whence they reach the melting pot 70 one at a time by detaining and releasing mechanism similar to that previously described. The depositing action is illustrated in Figure 10, wherein in full lines the cradle is shown as approaching the roller platform 26 and in dotted 75

lines as having deposited its layer of pigs thereon. The downward motion of the cradle is, however, allowed to continue somewhat and the swinging members 66 are thereby thrust apart owing to the fact that diverging plates 80 fitted thereto encounter fixed ramps 81. In this separating motion rollers or studs 82 fitted to the backs of the swinging members 66 push back flaps 83 pivoted at 84, and when the rollers or studs 82 reach a position beyond the bottom edge of the flaps 83, the latter fall back into their normal position, so that, when the elevator is reversed and the cradle commences its upward travel, the rollers or studs 82 bear on the outside of the flaps 83, thereby maintaining the swinging members 66 in their extended position. This action is, however, maintained only over the first portion of the upward travel, since above the flaps 83 there are gaps 85 which, when reached by the rollers or studs 82, permit the swinging members 66 to fall inwardly to their normal position. The object of thus keeping them separated until, on its return motion, the cradle is clear of the roller platform 26, is to prevent the possibility of its again lifting the pigs which have just been deposited and have failed to roll down the platform 26 owing to the presence of other pigs lower down the platform or for any other cause. Reversal of the elevator after the cradle has passed the roller platform 26 is effected by means of a switch E, actuated by a ramp 86 carried by the cross beam 69.

It will be appreciated that, as in the previously described apparatus, rotation through a right angle of the group of pigs in operative relationship with the elevator is required after the lifting of each layer. This is effected by means of a turntable 87 rotated from the electric motor 63 operating through worm gearing 88, bevel gearing 89 and spur gearing 90, adapted to drive a spindle 91 on which the turntable 87 is mounted, these elements being clearly seen in Figures 7 and 8. Each of the tables 2 and the turntable 87 are provided with engagement mechanism similar to that adopted in the apparatus previously described and a description thereof, in the present instance, is therefore unnecessary. The spindle 91 of the turntable 87 is further provided with a spur wheel 92 meshing with a gear wheel 93 mounted on a spindle 94 which also carries a disc 95 having five notches 96 corresponding to the five layers of pigs in each group, and spaced as indicated in Figure 8. Co-operating with these notches is a lever 97 pivoted at 98 and having attached at its outer end a cord or chain 99 passed over an idler wheel 100 and provided at its lower end with a weight 101. The cord or chain 99 is adapted to operate a switch G in the circuit of the motor 63, in such a manner that, on rotation of the disc 95 in a clockwise direction, which is that imparted to it by the motor 63, when the end of the lever 97 drops into one of the notches 96, the motor 63 is stopped. The period of stoppage, of course, corresponds to that during which the cradle of the elevator is travelling downwardly toward the group of pigs and is engaging and lifting the uppermost layer. After this action has occurred, rotation of the group of pigs is necessary and, accordingly, the motor 63 must be started. This is effected by a switch D actuated by a ramp 102 carried by the cross beam 69. The construction of the mechanism acted upon by the ramp 102, however, is such that the switch D is operated only on the upward motion of the cradle so that, when the latter returns after depositing its load of pigs on the platform 26, the switch D

is not again operated to restart the motor 63. Obviously, the action of the ramp 102 on the switch D must be maintained for such a time as to allow sufficient rotation of the disc 95 to cause the lever 97 to be ejected from the notch in which it has been resting. Rotation of the group of pigs through a right angle corresponds to such a rotation of the disc 95 that the end of the lever 97 drops into the succeeding notch 96 and operates to stop the motor 63.

After the table beneath the elevator has been emptied, it is, of course, necessary to restart the conveyor in order that the next table in succession may be brought into co-operative relationship with the elevator. For this purpose a switch H is provided actuated by a lever 103 carried by the disc 95. As indicated in Figure 8, between the notch 96 corresponding to the lowest layer of pigs and that corresponding to the highest layer, the angular distance is double that between the remaining notches. Thus, after the lowest layer has been removed, the turntable 87 revolves through 180° in order that the elements of the engagement mechanism respectively on the on-coming table 2 and the turntable 87 may be in their proper mutual engagement position. This rotation of the turntable having been effected, the lever 103 actuates the switch H, with the result that the motor 61 is restarted and the conveyor travels forward until the button or roller 30 65 next in succession operates to open the switch B. This, of course, occurs when the next succeeding table 2 has been brought into co-operative relationship with the elevator and the above-described sequence of operations is then repeated. As above mentioned, the switch B recloses itself, but not until the lever 103 has rotated sufficiently to allow the switch H to reopen.

In order, after the last table has been emptied and has passed from beneath the elevator, to stop the conveyor and the elevator, a switch F is provided. This affects the circuit of both the motors 61 and 62 so that these motors are stopped. The switch F is actuated by a button, roller or the like attached to the last of the series of tables 2 or to a point on the conveyor chain 6 in proximity thereto. Thus, after all the tables have been emptied, the whole apparatus is entirely disconnected from the power circuit.

Figures 11 and 12 taken together constitute a complete electrical diagram of the apparatus illustrated in Figures 6 to 10, certain of the items of that apparatus being shown in Figures 11 and 12 and marked with corresponding references. For the sake of avoiding undue complication of the diagram, however, certain features of ordinary construction which would necessarily be embodied in the apparatus, for example, shunt windings of the motors, automatic starting rheostats, overload relays, are omitted, their method of connection in the system being perfectly obvious to those skilled in the art and constituting no feature of the present invention.

The elements which control the action of the various items of electrical apparatus are assembled on a board 127 indicated in Figure 12. This board is represented as provided along its right-hand margin with a series of terminals, to each of which there is allocated a reference letter or numeral. In order to facilitate tracing out the various connections on the diagram, the same reference letters or numerals are respectively attached to various details of the apparatus which are directly connected to the corresponding terminals on the board 127. In order further to facilitate

tracing connections, where necessary, from Figure 11 to Figure 12, the electrical leads which, owing to the necessity of employing two figures to represent a single diagram, are broken, have been marked correspondingly on these figures with the references *a*, *b*, . . . *w*, *x*. These markings, however, do not constitute references in the normal sense of the term and will not be mentioned in the following description of the diagram.

The electrical supply to the apparatus is assumed to be direct current through a main double-pole switch 128 which at all times when the apparatus is in operation would be closed, thus making the terminals 129 and 130 respectively permanently positive and negative. Further, owing to certain fixed connections, certain other points in the apparatus will always possess a given polarity during the whole time that the switch 128 is closed. Thus the terminal W of the "start" push button 131 is permanently positive, being connected to terminal 129 by leads 132, 133. Similarly the lead 134 connected to lead 133 renders the contact 135 of the switch E permanently positive, and, further, the contact 136 of the switch D and the contacts 137 and 138 of the switch B are rendered positive from lead 134 via leads 139, 140, 141, 142. Similarly, from the negative terminal 130 via lead 143, the terminals LC and LT are permanently negative, and this remark also applies to terminal 111 and point 144 connected with terminal LT via leads 145, 146. In the ensuing description, therefore, certain circuits will be traced between these points as being positive and negative respectively.

As above described, the first action required is the loading of the tables 2 with the groups of pigs and for this purpose they must be successively brought to and retained in position "X" immediately above the switch A, this switch being thereby opened so that the conveyor motor 61 is stopped. Normally, however, the switch is closed and on pressing the "start" push button 131, circuit is established from positive at the terminal 40 W of the push button, through the push button, leads 147, 148, relay coil 149, to negative at 144. This results in closing relay switch 150 and circuit is then made from positive at contact 137 of switch B, through the switch, lead 151, terminal 50 112, lead 152, switch 150, coil 153 of conveyor motor contactor, lead 154, terminal 113, lead 155, switch A, lead 156, to negative at terminal 111. This closes the holding-on switch 157 and the main conveyor motor switch 158. Circuit to the 55 conveyor motor is then established from positive at terminal 129, via lead 159, switch 158, lead 160, terminal AC, lead 161, conveyor motor 61, lead 162 to negative at terminal LC. The conveyor then operates to bring the first table 2 to position "X" at which it opens the switch A, thus 60 stopping the conveyor. As explained above, however, this switch is of such a construction that, after a certain period, it automatically recloses itself; hence, when the table 2, which is in the loading position, has been loaded, on again depressing the "start" push button, the conveyor motor 61 is 65 started and the conveyor travels until the succeeding table 2 breaks circuit at the switch A, this cycle of events being repeated for the loading operation of each table.

On arrival of the table 2 in position "Y" in which it is in co-operative relationship with the elevator, the switch B breaks circuit between its contacts 112 and 137 and makes circuit between 70 contacts 138 and 163. This breaks the circuit of

the conveyor motor so that the table is stopped in position "Y", and makes circuit from positive at contact 138, switch B, lead 164, switch F, lead 165, terminal 114, lead 166, relay coil 167 to negative at 144; switches 168, 169 and 170 are thus closed. This completes circuit from positive at contact 138, switch B, leads 164, 171, terminal 115, lead 172, switch 169, lead 173, arm of interlock switch 174, contact 175, leads 176, 177, terminal 123, lead 178, switch C, lead 179, terminal 122, lead 180, elevator motor "down" contactor coil 181, leads 182, 183, 184, to negative at 144; switches 185, 186, 187, 188 are thereby closed. The circuit of the elevator motor is thus completed from positive at terminal 129, leads 159, 189, 190, switch 186, leads 191, 192, terminal Y, lead 193, field-winding 194 of motor 62, lead 195, terminal Z, lead 196, switch 187, lead 197, terminal LE, lead 198, armature of motor 62, lead 199, terminal AE, lead 200, switch 188, leads 201 and 202, to negative at terminal LT. The elevator is thus started so that the cradle 66 travels in the downward direction in order to pick up the layer of pigs which, for the time being, is uppermost. As this occurs, the switch C is actuated by means of the plunger 71 as described with reference to Figure 9. Accordingly, circuit is broken between the contacts 122 and 123 of the switch C and made at contacts 120 and 121. This operates to de-energize the elevator contactor coil 181, whereby the switches 185, 186, 187 and 188 are opened and the motor 62 stopped.

Circuit whereby this motor is restarted in the opposite direction is, however, completed by the contacts 120 and 121 of switch C. This circuit is from positive at terminal W, leads 203, 204, switch 188, leads 205, 206, terminal 121, lead 207, switch C (lower contacts) lead 208, terminal 120, leads 209, 210, terminal 119, lead 211, switch E, lead 212, terminal 118, lead 213, elevator motor "up" contactor coil 214, leads 215, 183, 184, to negative at 144. This closes switches 216, 217, 218, 219, 220 and starts the elevator motor in the reverse direction so that the cradle 66 is raised. For this purpose circuit is completed from positive at terminal 129 leads 159, 189, switch 218, lead 192, terminal Y, lead 193, field-winding 194 of elevator motor 62, lead 195, terminal Z, lead 196, switch 219, lead 200, terminal AE, lead 199, armature of elevator motor 62, lead 198, terminal LE, leads 197, 221, switch 220, lead 202, to negative at LT. As the cradle 66 begins to ascend switch C breaks circuit at contacts 120, 121 and remakes it at contacts 122, 123. The contactor coil 214 is not, however, thereby de-energized, its circuit being maintained through the holding-on switch 217. As above described, the cradle 66 on passing the switch D actuates it to start the turntable motor 63. The electrical circuits operative to this end will be described below. As the elevator motor continues to operate, the cradle actuates the switch E to break circuit at contacts 118, 119 and to make it at 117 and 135; thereby the circuit of the contactor coil 214 is broken and the switches which it controls opened, stopping the elevator motor.

Completion of circuit at contacts 117 and 135 of switch E results in restarting the elevator motor in the opposite direction, the circuit being from positive at contact 135, through switch E, lead 222, terminal 117, lead 223, reversing relay coil 224, lead 184, to negative at 144. This closes switches 225 and 226, establishing circuit from positive at terminal W via lead 203, switch 170, lead 227, switch 225, leads 228, 176, 177, terminal 75

123, lead 178, switch C, lead 179, terminal 122, lead 180, contactor coil 181, leads 182, 183, 184, to negative at 144. This closes the main switches 186, 187 and 188 of the circuit which, as above explained, causes the elevator motor to be started in such a direction that the cradle 66 travels downwards and the sequence of operations is then repeated. As soon as the cradle 66 leaves the switch E circuit is opened at contacts 117 and 135 and reclosed at 118, 119. The circuit of coil 181, however, remains closed through holding-on switch 185.

It will be noticed that, once the elevator has been started by one of the tables 2 arriving at position "Y", it will continue by virtue of its co-operation with switches C and E to be repeatedly reversed so that the cradle 66 travels alternately in the upward and downward direction as required until the table has been emptied. In performing these repeated reversals, however, circuit is established independently of the interlock switch, this switch being provided for the purpose of ensuring that when the elevator is started by the arrival of a table 2 at position "Y" it shall travel in the appropriate direction. Thus, in the above description, it is assumed that initial travel in the downward direction in order to take up a layer of pigs was required, and, accordingly, previous downward travel of the cradle would have served to lock the interlock switch so that its arm 174 bore on contact 175. Had, however, the travel of the cradle, before the elevator motor 62 was previously stopped, been in the upward direction, the arm 229 of the interlock switch would have been bearing on the contact 230, contact between the arm 174 and contact 175 being broken. The action of the mechanism to effect this result is well known and need not be further alluded to. Contact being made between the arm 229 and contact 230, circuit would be established from positive at contact 138 through switch B leads 164, 171, terminal 115, lead 172, switch 169, lead 173, arm 229, contact 230, leads 231, 210, terminal 119, lead 211, switch E, lead 212, terminal 118, lead 213, contactor coil 214, leads 215, 183, 184, to negative at 144. This serves to close switches 218, 219 and 220, whereby the elevator motor is started in such a direction as to cause the cradle to travel upwardly as previously described.

The action of the switch D in controlling the turntable motor 63 will now be described. As the cradle 66 passes the switch D, circuit is broken at contacts 124 and 136 and made at contacts 125 and 232. This establishes circuit from positive at contact 232 through switch D, lead 233, terminal 125, lead 234, switch 216, lead 235, turntable motor contactor coil 236, leads 237, 184, to negative at 144. This operates to close switches 238 and 239, and establishes circuit from positive at terminal 129, leads 159, 189, switch 239, lead 240, terminal AT, lead 241, turntable motor 63, lead 242, to negative at terminal LT. Geared to revolve with the motor 63 is the star-wheel 95, whereby switch G is actuated. On rotation of the star-wheel 95 the switch G bridges contacts 126, 243, whereby, shortly after the turntable motor 63 has been started, a holding-on circuit is completed from positive at contact 137 of switch B via lead 244, switch G, lead 245, terminal 128, lead 246, switch 238, contactor coil 236, leads 237, 184, to negative at 144. When, however, the turntable motor 63 has revolved sufficiently to turn the table 2 for the time being in position "Y" through a right angle, the star-wheel 95 operates to open the switch G whereby the turntable

contactor 236 is de-energized and its switches opened thereby stopping the motor 63. It is then re-started as the cradle 66 on its succeeding upward travel passes the switch D and the above cycle of operations repeated. It will, however, be observed that the form of the star-wheel 95 is such that, after the last layer of pigs has been lifted, the switch G is maintained closed for a period twice the length of its previous closures in order that, for the reasons above mentioned, the turntable shall be rotated through 180° instead of 90°.

In order to re-start the conveyor after a table has been emptied, the switch H comes into operation. This is driven in such a manner as to close contacts at 116 after the last layer of pigs has been lifted, and before the cradle 66 reaches the switch E. When actuation of this switch by the cradle occurs, the contacts 117 and 135 are bridged and the reversing relay coil 224 excited as above described. Circuit is then established from positive at contact 137 of switch B through lead 244, contacts 116 of switch H, lead 247, terminal 116, lead 248, switch 226, lead 249, conveyor contactor coil 153, lead 154, terminal 113, lead 155, self-closing switch A, lead 156 to negative at terminal 111; thereby switches 157 and 158 are closed and the conveyor motor 61 started as above set forth. The conveyor then travels until the succeeding table arrives at position "Y" at which it operates switch B which serves to stop the conveyor and control the movements of the elevator and turntable in the manner above described.

After the last table of the series has been emptied and has left position "Y", switch F is opened by the conveyor as above stated. This operates to break the circuit of the relay coil 167, allowing switches 168, 169, and 170 to open and stop the elevator. Motion of the conveyor, however, continues until the switch of the motor 61 is opened by actuation of the switch A when the leading table of the series arrives at position "X".

While two examples of apparatus in accordance with the invention have been described and illustrated, it is obvious that many other combinations within its scope might be devised. Further, features above described might be combined in other ways: for instance, in the apparatus depicted in Figures 1 to 5, in place of driving the conveyor intermittently from a continuously revolving shaft, it might be actuated by a separate electric motor under automatic control, as described with reference to Figures 6 to 10.

What I claim and desire to secure by Letters Patent of the United States is:—

1. Apparatus for the automatic delivery of metal pigs, comprising in combination a conveyor in co-operative relationship with an elevator, a series of tables on said conveyor for the reception of groups of pigs, each of said tables being revoluble about an axis at right angles to its supporting surface, means for rotating the table in said series for the time being in operative relationship with the elevator through a right angle after each layer of pigs in a group on said table has been lifted and a delivery device, on which each layer of lifted pigs is deposited.

2. Apparatus for the automatic delivery of metal pigs stacked in superposed layers wherein the pigs in each layer lie at right angles to the pigs in the next layer, comprising in combination a conveyor in co-operative relationship with an elevator constituted by upper and lower sprocket wheels and endless travelling chain mechanism, a series of lifting cradles on said chain mechanism,

and means operatively associated with the cradles for rotating the stack of pigs relatively to the conveyor to bring the top layer of pigs into position to be lifted, and means for causing the cradles selectively to lift the top layer of pigs.

3. Apparatus for the automatic delivery of metal pigs, comprising in combination a conveyor in co-operative relationship with an elevator, a series of tables on said conveyor for the reception of groups of pigs, each of said tables being revoluble about an axis at right angles to its supporting surface, a continuously rotating shaft, a friction slip device comprising driving and driven members in operative connection with said shaft, a mutual engagement mechanism associated with the driven member of said slip device and with each of said tables and means, controlled in synchronism with the movements of said elevator, for intermittently arresting rotation of said driven member.

4. Apparatus for the automatic delivery of metal pigs, comprising in combination a conveyor in co-operative relationship with an elevator, a series of tables on said conveyor for the reception of groups of pigs, each of said tables being revoluble about an axis at right angles to its supporting surface, a continuously rotating shaft, a friction slip device comprising driving and driven members in operative connection with said shaft, a mutual engagement mechanism associated with the driven member of said slip device and with each of said tables, a disc in driving relationship with said driven member, projections on said disc, a plunger movable into or out of engagement with any of said projections, and a pivoted lever for actuating said plunger in synchronism with the movements of said elevator.

5. Apparatus for the automatic delivery of metal pigs, comprising in combination a conveyor in co-operative relationship with an elevator constituted by upper and lower sprocket wheels and endless travelling chain mechanism, a series of lifting cradles on said chain mechanism, each of said cradles comprising a pair of pivoted members capable of swinging toward or away from each other, means for rotating said sprocket wheels continuously in the same direction, a projecting element on each of said pivoted members and a plurality of cams each of which is adapted selectively to engage one of the projecting elements thereby holding the pivoted members to which they are engaged out of engagement with selected layers of pigs.

6. Apparatus for the automatic delivery of metal pigs, comprising in combination a conveyor in co-operative relationship with an elevator, a cradle on said elevator, mechanism on said cradle for lifting the uppermost layer of metal pigs in a group, a delivery device and means for raising said cradle from the position in which it is effective to lift a layer of pigs from a group in operative relationship with said elevator to that in which it deposits said pigs on said delivery device and for returning said cradle by the same path.

7. Apparatus for the automatic delivery of metal pigs comprising in combination a conveyor in co-operative relationship with an elevator, an electric driving motor for said elevator, a cradle on said elevator, mechanism on said cradle for lifting the uppermost layer of metal pigs in a group, a delivery device, reversing switches in the circuit of said motor and actuating means for said switches automatically operating when said cradle respectively is in posi-

tion to lift a layer of pigs from said conveyor and has deposited said layer on said delivery device.

8. Apparatus for the automatic delivery of metal pigs, comprising in combination a conveyor in co-operative relationship with an elevator, an electric driving motor for said elevator, a lifting cradle on said elevator, a delivery device, reversing switches in the circuit of said motor and actuating means for said switches automatically operative when said cradle respectively is in operative lifting position relatively to the top layer of a group of pigs in operative relationship with said elevator and has deposited said layer on said delivery device.

9. Apparatus as in claim 8, wherein the actuating means effective for reversal when the cradle is in position operative for lifting includes an element so located as, when the cradle travels downwards, to bear on the successive top layer of pigs.

10. Apparatus for the automatic delivery of metal pigs, comprising in combination a conveyor in co-operative relationship with an elevator, a series of tables on said conveyor for the reception of groups of pigs, each of said tables being revoluble about an axis at right angles to its supporting surface, an electric motor for rotating the table in said series for the time being in operative relationship with said elevator through a right angle after each layer of pigs on said table on said table has been lifted, a starting switch in the circuit of said motor and actuating means for said switch operated by said elevator after each of said layers has been lifted.

11. Apparatus for the automatic delivery of metal pigs, comprising in combination a conveyor in co-operative relationship with an elevator, a series of tables on said conveyor for the reception of groups of pigs, each of said tables being revoluble about an axis at right angles to its supporting surface, an electric motor for rotating the table for the time being in operative relationship with said elevator through a right angle after each layer of pigs on said table has been lifted, a switch in the circuit of said motor and means, actuated on rotation of said table, whereby, on completion of rotation through a right angle, said switch is opened and said motor stopped.

12. Apparatus for the automatic delivery of metal pigs, comprising in combination a conveyor in co-operative relationship with an elevator, an electric driving motor for said conveyor, a switch in the circuit of said motor, mechanism automatically actuated by the motion of said conveyor whereby said switch is opened when said conveyor is in a position such that a group of metal pigs on said conveyor is in operative relationship with said elevator, and mechanism for closing said switch automatically actuated on removal of the lowest layer of pigs in a group in operative relationship with said elevator.

13. Apparatus for the automatic delivery of metal pigs, comprising in combination a conveyor in co-operative relationship with an elevator, an electric driving motor for said conveyor, a switch in the circuit of said motor, mechanism automatically actuated by the motion of said conveyor whereby said switch is opened when said conveyor is in a position such that a group of metal pigs on said conveyor is in operative relationship with said elevator, a further switch in the circuit of said motor, a series of tables on said conveyor for the reception of groups of pigs, each of said tables being revoluble about

an axis at right angles to its supporting surface, a motor for periodically rotating the table in said series in operative relationship with said elevator through a right angle and means for closing said switch automatically actuated by said second-mentioned motor.

14. Apparatus for the automatic delivery of metal pigs, comprising in combination a conveyor in co-operative relationship with an elevator, an electric driving motor for said conveyor, a switch in the circuit of said motor, mechanism automatically actuated by the motion of said conveyor whereby said switch is opened when said conveyor is in a position such that a group of metal pigs on said conveyor is in operative relationship with said elevator, an electric driving motor for said elevator, a switch in the circuit of said motors respectively actuating said conveyor and said elevator and means for opening said switch automatically actuated on motion of said conveyor after the last group of pigs has been removed from its position of operative relationship with said elevator.

15. Apparatus as in claim 6, including outwardly inclined ramps located in that part of the path of the cradle traversed immediately after said layer of pigs has been deposited on said delivery device and pivoted flaps in proximity to said ramps, whereby the elements of said cradle are separated clear of said layer of pigs and are maintained so separated during the return travel of said cradle past said layer. 5

16. Apparatus for the automatic delivery of metal pigs, comprising in combination a conveyor in co-operative relationship with an elevator, a series of tables on said conveyor for the reception of groups of pigs, each of said tables being revoluble about an axis at right angles to its supporting surface, and means in operative association with said elevator for intermittently rotating the table for the time being in operative relationship with said elevator about its axis through a right angle. 10 15 20

VINCENT TOBIA.
